SHOE SOLE CONSTRUCTION

Norval Burris Griffin, Portsmouth, Ohio, assignor
to The Selby Shoe Company, a corporation of
Ohio

Application September 24, 1935, Serial No. 41,916

2 Claims. (Cl. 36—71)

This invention relates to women's shoes, and is particularly directed to a shoe incorporating an improved sole structure. More specifically, the improvement resides in the structure of the sole corresponding to that plantar portion of the foot posterior to the distal ends of the metatarsal bones.

Heeled shoes, particularly the higher heeled type, tip the foot forward on the distal heads 10 of the metatarsal bones and the toes, creating a space between the foot and the shoe sole at the juncture of the shank and the forepart of the shoe. The higher the heel the greater the space. It is necessary for the foot to bridge this 15 space and the foot is therefore without proper support.

The absence of contact and adequate support as above pointed out frequently causes pain in the plantar surface of the foot. This pain is brought about by strain on the plantar ligament 20 and tendons. The metatarsal bones extend from the tarsal bones, commonly called the instep, to the base of the toes. They have rounded heads at their forward ends, which heads are disposed 25 in a transverse row and in high heeled shoes are called upon to support more than their share of the weight of the body. Lack of support or impost at the section directly back of these rounded heads sometimes results in displacement of the 30 metatarsal bones and causes a great deal of pain. There is abnormal distribution of weight, too much falling on the heads of these metatarsal bones due to the lack of support for the area of the foot just to the rear of the ball of the foot. This 35 causes a concentration or focus of pressure at one spot, and the result at times is a very painful callous. The results of displaced metatarsal bones are far-reaching, since it is obvious if the bones are misplaced, so are the muscles and 40 tendons, and the foot action is greatly impaired. Accordingly, it is necessary that the shoe be of a construction which adequately supports not only the forward ends of these metatarsal bones in normal position but also the area just back 45 of the ball of the foot before the foot action can be proper.

It is, therefore, the object of the present invention to provide a shoe sole construction, particularly for higher heeled shoes, which provides 50 a full length tread base or continuous support for the foot throughout the length of the shoe from the heel to the toe, particularly at the region posterior to the distal ends of the metatarsal bones. Accordingly, the invention may be accurately recited as residing in the provision of 55

an impost pad perfectly located and formed within the sole structure of the shoe. This pad relieves the strain on the plantar ligament and tendons, and properly distributes the weight to the heads of the metatarsals, thus maintaining their proper anatomical relation. The improvement tends to avoid displacement of the metatarsal bones and partially corrects conditions where these bones have fallen from their normal positions or the positions where they support 10 the weight of the body as intended.

It is a further object to provide a sole structure incorporating an impost pad which is of a shape particularly carefully fitted transversely of the foot. In other words, these metatarsal bones 15 providing their rounded forward supporting ends have a definite position in relation to the tread surface. If this position is not maintained, foot trouble ensues. The pad herein incorporated has a carefully developed transverse shape for maintaining a more comfortable position of the bones. In constructing a shoe incorporating the present improvement, the manufacturer builds his pad in accordance with the height of the heel. In other words, as the heel height is increased the pad 20 structure must be altered as to any cross section.

Other objects and further advantages will be more fully apparent from a description of the accompanying drawing, in which:

Figure 1 is a top plan view of a shoe incorporating the improvement, portions of the upper and liner being removed for fully illustrating the improved sole structure.

Figure 2 is a sectional view taken on line 2—2, Fig. 1, the view being partially fragmentary 35 and broken away for more fully illustrating the sole structure toward the ball of the foot.

Figure 3 is a general view taken on line 3—3, Fig. 2, further detailing the sole structure.

Figure 4 is a perspective view of the impost 40 pad removed from the shoe and looking generally toward the top thereof.

Figure 5 is a bottom plan view of the pad.

Referring to the drawing, the pad has been illustrated incorporated within the shoe and separately. The shoe illustrated includes the usual structure. The upper of the shoe is indicated at 10; the outsole at 11; the insole at 12; heel at 13; and the sock lining at 14.

Any sort of shank stiffener or arch support 50 (not shown) may be incorporated along the instep of the shoe. The impost pad herein concerned is illustrated at 15. This pad is located in the shoe at what may be called the juncture of the instep or shank and the forepart. The 55

pad may be constructed of any suitable material being preferably formed of a soft grade of rubber or a rubber which may be described as extremely pliant and yet capable of adequately supporting 5 when held in position.

The pad as viewed in top plan view is of triangular shape having well-rounded corners 16. It is relatively thick at the center and tapers off to feather edges 17. Its contour may be described 10 as follows:

In longitudinal section (see Figure 2) its curvature is such as to fit snugly to the curvature of the insole. Its upper surface 18 is slightly convexed and gradually merges with the forepart or 15 horizontally disposed portion 20 of the sole structure. Thus, as a space is created by the provision of a high heel, the pad fills out this space and provides the necessary support by continuance of the tread. The pad is specifically designed to fill 20 out the space occurring between the pad and the insole.

In transverse cross section (see Figure 3) the pad is of a contour fitting the curvature of the insole and the curvature of the upper so that it lies 25 snugly against these parts. Its upper surface is slightly convexed fitting the natural transverse curvature of the sole of the foot posterior to the distal ends of the metatarsal bones. It has been determined that in order to fit this shape so that 30 the foot closely and snugly contacts the pad the pad should be of greater height or thickness toward the inner side of the foot as at 21, that is, on the inside of the longitudinal axis thereof.

Also, in order to provide full support for the 35 foot not only longitudinally but transversely the pad overhangs or extends beyond the inner edge margin 22 of the insole as at 23 (see Figure 1). This portion of the pad lies snugly against the upper. The highest point and the thickest portion 40 of the pad is substantially over the inner edge margin of the insole or very slightly to the inside thereof. With the transverse contour as stated, the transversely aligned forward ends of the metatarsal bones are maintained in a more 45 comfortable position or the position where they best support the weight of the body.

The results of displaced metatarsal bones are well known. A great deal of pain is attendant the displacement since the tendons or muscles 50 overlying and surrounding the bones are badly stretched or pushed out of position and strained and there may be some impingement on nerves near the metatarsals. Not only is there resultant pain from the muscular or tendon condition or 55 pressure on nerves, but the localized pressure re-

sulting therefrom causes a painful callous. The present sole construction provides an impost pad supporting the forward end of the arch of the foot, which pad is sufficiently solid to support the weight, but at the same time is resilient enough 5 to take up or absorb shock.

Having described my invention, I claim:

1. In a high-heeled shoe, a sole construction embodying an insole having a portion of narrowest width at the juncture of the shank and the 10 forepart of the shoe and curving outwardly forwardly of this point along the inner edge, an impost pad adapted to support the forward end of the metatarsal arch of the foot and filling the space normally occurring between the foot and 15 the shoe sole at the region posterior of the distal ends of the metatarsal bones at the juncture of the shank and the forepart of the shoe, which space occurs due to the increased heel height, the longitudinal cross section of the pad being varied 20 in thickness so as to form an uninterrupted continuation of the curvature of the shoe sole and the transverse section being such as to provide a portion of greatest thickness disposed at the inner side of the central line of the shoe, and the 25 inner margin of the pad overlying the shoe upper adjacent the narrowest portion of the insole and forwardly and adjacent to substantially the entire outwardly forwardly curved inner edge 30 thereof.

2. In a high-heeled shoe, a sole construction embodying an insole having a portion of narrowest width at the juncture of the shank and the forepart of the shoe and curving outwardly forwardly of this point along both the inner and outer edge, an impost pad adapted to support the forward end of the metatarsal arch of the foot and filling the space normally occurring between the foot and the shoe sole at the region posterior of the distal ends of the metatarsal 35 bones at the juncture of the shank and the forepart of the shoe, which space occurs due to the increased heel height, the longitudinal cross section of the pad being varied in thickness so as to form an uninterrupted continuation of the curvature of the shoe sole and the transverse section 40 being such as to provide a portion of greatest thickness disposed at the inner side of the central line of the shoe, and both the inner and outer margins of the pad overlying the shoe upper adjacent the narrowest portion of the insole and forwardly and adjacent to substantially the entire outwardly forwardly curved inner and outer edges thereof.

pad may be constructed of any suitable material being preferably formed of a soft grade of rubber or a rubber which may be described as extremely pliant and yet capable of adequately supporting 5 when held in position.

The pad as viewed in top plan view is of triangular shape having well-rounded corners 16. It is relatively thick at the center and tapers off to feather edges 17. Its contour may be described 10 as follows:

In longitudinal section (see Figure 2) its curvature is such as to fit snugly to the curvature of the insole. Its upper surface 18 is slightly convexed and gradually merges with the forepart or 15 horizontally disposed portion 20 of the sole structure. Thus, as a space is created by the provision of a high heel, the pad fills out this space and provides the necessary support by continuance of the tread. The pad is specifically designed to fill 20 out the space occurring between the pad and the insole.

In transverse cross section (see Figure 3) the pad is of a contour fitting the curvature of the insole and the curvature of the upper so that it lies 25 snugly against these parts. Its upper surface is slightly convexed fitting the natural transverse curvature of the sole of the foot posterior to the distal ends of the metatarsal bones. It has been determined that in order to fit this shape so that 30 the foot closely and snugly contacts the pad the pad should be of greater height or thickness toward the inner side of the foot as at 21, that is, on the inside of the longitudinal axis thereof.

Also, in order to provide full support for the 35 foot not only longitudinally but transversely the pad overhangs or extends beyond the inner edge margin 22 of the insole as at 23 (see Figure 1). This portion of the pad lies snugly against the upper. The highest point and the thickest portion 40 of the pad is substantially over the inner edge margin of the insole or very slightly to the inside thereof. With the transverse contour as stated, the transversely aligned forward ends of the metatarsal bones are maintained in a more 45 comfortable position or the position where they best support the weight of the body.

The results of displaced metatarsal bones are well known. A great deal of pain is attendant the displacement since the tendons or muscles 50 overlying and surrounding the bones are badly stretched or pushed out of position and strained and there may be some impingement on nerves near the metatarsals. Not only is there resultant pain from the muscular or tendon condition or 55 pressure on nerves, but the localized pressure re-

sulting therefrom causes a painful callous. The present sole construction provides an impost pad supporting the forward end of the arch of the foot, which pad is sufficiently solid to support the weight, but at the same time is resilient enough 5 to take up or absorb shock.

Having described my invention, I claim:

1. In a high-heeled shoe, a sole construction embodying an insole having a portion of narrowest width at the juncture of the shank and the 10 forepart of the shoe and curving outwardly forwardly of this point along the inner edge, an impost pad adapted to support the forward end of the metatarsal arch of the foot and filling the space normally occurring between the foot and 15 the shoe sole at the region posterior of the distal ends of the metatarsal bones at the juncture of the shank and the forepart of the shoe, which space occurs due to the increased heel height, the longitudinal cross section of the pad being varied 20 in thickness so as to form an uninterrupted continuation of the curvature of the shoe sole and the transverse section being such as to provide a portion of greatest thickness disposed at the inner side of the central line of the shoe, and the 25 inner margin of the pad overlying the shoe upper adjacent the narrowest portion of the insole and forwardly and adjacent to substantially the entire outwardly forwardly curved inner edge 30 thereof.

2. In a high-heeled shoe, a sole construction embodying an insole having a portion of narrowest width at the juncture of the shank and the forepart of the shoe and curving outwardly forwardly of this point along both the inner and outer edge, an impost pad adapted to support the forward end of the metatarsal arch of the foot and filling the space normally occurring between the foot and the shoe sole at the region posterior of the distal ends of the metatarsal 35 bones at the juncture of the shank and the forepart of the shoe, which space occurs due to the increased heel height, the longitudinal cross section of the pad being varied in thickness so as to form an uninterrupted continuation of the curvature of the shoe sole and the transverse section 40 being such as to provide a portion of greatest thickness disposed at the inner side of the central line of the shoe, and both the inner and outer margins of the pad overlying the shoe upper adjacent the narrowest portion of the insole and forwardly and adjacent to substantially the entire outwardly forwardly curved inner and outer edges thereof.
